(57) **CLAIM**

The ornamental design for a Bluetooth tracker tag, as shown and described.

DESCRIPTION

FIG. 1 is a perspective view of a Bluetooth tracker tag, in accordance with our design;

FIG. 2 is top view of the Bluetooth tracker tag of FIG. 1; FIG. 3 is a front view of the Bluetooth tracker tag of FIG. 1;

FIG. 4 is a rear view of the Bluetooth tracker tag of FIG. 1; FIG. 5 is a bottom view of the Bluetooth tracker tag of FIG. 1;

FIG. 6 is a left-side view of the Bluetooth tracker tag of FIG. 1; and,

FIG. 7 is a right-side view of the Bluetooth tracker tag of FIG. 1.

The dashed broken lines in the drawings define unclaimed subject matter that forms no part of the claimed design.
